VEGETABLE COMMINUTOR RECEPTACLE
OR THE LIKE

Walter Häuptli, Bruscholz, Aarburg, Switzerland, assignor to Rotel AG, Aarburg, Switzerland, a corporation of Switzerland

Filed June 19, 1964, Ser. No. 80,476

Term of patent 7 years

The characteristic feature of the design resides in the particular configuration and arrangement of the cover portion and its associated lid element.

I claim:

The ornamental design for a vegetable comminutor receptacle or the like, substantially as shown and described.
